UNITED STATES PATENT OFFICE.

LOUIS NEWMAN, OF CHICAGO, ILLINOIS.

TRAIN OF PASSENGER-CARS.

1,114,906.

Specification of Letters Patent.

Patented Oct. 27, 1914.

Application filed September 15, 1913. Serial No. 789,800.

To all whom it may concern:

Be it known that I, LOUIS NEWMAN, a citizen of the United States, residing at Chicago, in the county of Cook and State of Illinois, have invented certain new and useful Improvements in Trains of Passenger-Cars, of which the following is a specification.

My invention relates in general to trains of passenger cars and more particularly to trains of cars adapted for use upon elevated railways, subways and to other trains making stops too frequently to permit the collection of tickets and the like from the passengers between stations.

Prior to my invention it has been the custom upon elevated railways and the like to provide a guard at each pair of connected ends of the cars to open the doors for the exit and entrance of passengers, the tickets or fares being collected within each station before the passenger is permitted upon the platform. This has required that guards or door-keepers be provided in number only one less than the number of cars forming the train. It has necessitated also that a ticket or fare taker be provided at each station to receive the money and tickets of the passengers as they are admitted to the platform.

It is a principal object of the present invention to provide a train of cars which will require no gate-keeper for the platform and will reduce the number of guards required for the operation of the train to a minimum, effecting thereby a material saving in the cost of operating the road.

The trains employed prior to my invention have had a further disadvantage in that the passengers have left the cars and entered them through the same doors. This has caused much confusion and annoyance both to the guards and to the passengers themselves and has resulted in delaying the train as all of the passengers departing from the car must be upon the platform before the first passenger boarding the car can be admitted. My invention aims to overcome this disadvantage by causing the passengers to enter the car at a different point from that through which they depart so that passengers may be entering and leaving the train simultaneously and without crowding each other.

Other objects and advantages of the in-

vention will be apparent as it is better understood from the following description, when taken in connection with the accompanying drawing illustrating a preferred embodiment thereof.

On the drawing, Figure 1 is a horizontal section through a train unit embodying my invention when the train is standing at a station; Fig. 2 is a vertical section taken on the line 2-2 of Fig. 1, and Fig. 3 is an enlarged horizontal section of the central car of the train unit.

For the purpose of illustrating my invention I have shown the same embodied in a three-car train or train unit of the general type employed on elevated railways. The train may be composed of a single unit or of any desired number of units. In the present instance the train is shown as stopping at the platform 6 of an elevated station. The two end cars 7 preferably have no entrances or exits opening directly upon the platform, the passengers entering and leaving them through the center car 8, as will be later described, and to this end wide communicating doorways 9 are provided at the connected ends of the cars forming the train or train unit. The center car 8 has three doorways opening upon the platform, as shown in the drawings, the center one 10 being an entrance and the two end ones 11 exits.

Within the center car 8 and opposite the entrance 10 is provided a cage or railed-off portion 12 in which a single guard for the three cars may be stationed. Within the entrance 10 and extending across the car are provided rails 13 which direct the passengers to the guard as they enter the train. As this is the only entrance provided for the train or train unit all of the passengers must pass close to the guard in entering, who therefore can readily collect the fares. The exits 11 are located adjacent the ends of the center car where they are readily accessible to the passengers of all three cars. The three doorways of the center car are each provided with suitable doors, all under the control of the guard stationed in the cage or railed-off portion 12. In the present instance these doors are of the well-known collapsible type, those 14 of the exits 11 opening outwardly and those 15 of the entrance 10 opening inwardly. As shown in Fig. 3 three switches 16, one for each door, are provided in the guard's cage to control the

opening and closing of these doors through suitable electric motors and actuating mechanisms, indicated generally at 17. On the front of the guard's cage 12 is pivoted a 5 swinging bar or door 18 adapted to be connected to either of the rails 13 to direct the passengers toward a desired end of the train. If a bar be used it may merely drop down out of the way against the front of the 10 guard's cage or if a door be used it may close back against the front of the cage, as indicated at 19, to make both ends of the train freely accessible. As the guard is stationed at the center of the car 8 he is in a position 15 to see the entrance 10 and both exits 11 and is able to close each of the doors 14 and 15 as the passengers stop passing therethrough.

At the outer ends of the cars 7 are preferably provided doors 20, which may be used 20 either to communicate with other train units or as emergency exits to permit the passengers to leave the ends of the trains in case of accident.

Upon the platform is preferably provided 25 a pair of railed inclosures 21 each having a plurality of exit turnstiles 22. These inclosures are so arranged that one is disposed at each exit 11 when the train stops at the station. The passengers leaving the 30 train must then enter the inclosures and pass out through the turnstiles 22 which prevent their passengers from entering the train through the exits 11. The course of the entering passengers is indicated by the 35 arrows *a* and the course of the alighting passengers by the arrows *b*. It will be noted that the stream of passengers enters by the entrance 10 and divides toward each end of the train as it passes the guard. In leaving the train the passengers may leave 40 through the nearest exit 11 and pass out of the turnstiles onto the platform. This arrangement not only obviates the necessity of providing a ticket taker and a guard for 45 each end of the central car, as have heretofore been necessary, but it also obviates the necessity of causing the passengers desirous of entering the train to wait until all of the 50 passengers alighting at the station are upon the platform.

It is thought that the invention and many of its attendant advantages will be understood from the foregoing without further description and it is obvious that various 55 changes may be made in the arrangement and form of the cars without departing from the spirit or scope of the invention or sacrificing any of its advantages, the form hereinbefore disclosed being merely a preferred embodiment thereof.

I claim:

1. A passenger train composed of one or more units, each of said units comprising three connected cars communicating with 65 each other, one of said cars being provided

with an entrance and exits for all of said cars forming the unit.

2. A passenger train composed of one or more units, each of said units comprising a plurality of connected cars communicating 70 with each other, one of said cars having a single entrance and a plurality of exits for all of the cars.

3. A passenger train composed of one or more units, each of said units comprising 75 three or more connected cars communicating with each other, one of said cars being provided with an entrance for all of the cars forming said unit.

4. A passenger train composed of one or more units, each of said units comprising 80 three connected cars communicating with each other, the center one of which is provided with an entrance, and a plurality of exits for all of the cars.

5. A passenger train composed of one or more units, each of said units comprising three connected cars communicating with each other, the center car being provided at 85 its center with an entrance for all of the 90 cars and an exit at each end for the end car at that end of the train and for the adjacent end of the center car.

6. A passenger train comprising one or more train units, each unit composed of 95 three cars, the intermediate one of which is provided with end exits and an entrance in its side between said exits, the other two of said cars communicating with the intermediate car at its ends, whereby the unit is 100 served through a single entrance.

7. A passenger train comprising one or more train units, each such unit composed of three cars, a single entrance for serving all 105 of said cars, said entrance being provided in the side of the middle car of the unit, the other cars communicating with the intermediate car at its ends and the latter being provided with side exits near its ends

8. A passenger train comprising one or more train units, each such unit composed of three cars, one of said units having a single entrance provided in the side of the central car of the unit and said unit having 110 also a plurality of side exits arranged adjacent the coupled ends of the cars forming the unit.

9. The combination of a train comprising one or more units formed of communicating cars, one of said cars having a single central entrance for the unit and said unit being provided with an exit adjacent the coupled ends of two cars forming the same, and means for preventing passengers from entering the train through said exit.

10. The combination of a train composed of one or more units, each consisting of communicating cars, one of said cars being provided with a single entrance for all of the cars and having an exit at each end for 115

itself and for the car next adjacent said end, and means for preventing passengers from entering the train through the exits.

11. The combination of a train composed of one or more units, each consisting of communicating cars, one of said cars being provided with a single entrance and a plurality of exits for all of the cars, and a closure for each exit provided with an exit-
10 turnstile and fixed upon the station platform in position to prevent passengers from entering the train through the exit.

12. A passenger car having a centrally disposed entrance in one of its sides, members setting off a space within said entrance and forming a passageway adjacent the side of the car remote from said entrance from said set off space to either end of the car, a guard cage located opposite said entrance
15 and facing said passageway, and means for

directing passengers past said guard cage toward a desired end of the car.

13. The combination of a train unit of communicating cars provided with a single entrance for all the cars and having a plurality of exits, doors for all exits and said entrance and means for preventing the passengers from entering the train through the exits when all said closures are open.

14. The combination of a train composed of one or more units, each of said units being provided with a single entrance for serving all the cars of said unit and exits adjacent the coupled ends of the cars forming the unit, and means for preventing passengers from entering the train through the exits.

LOUIS NEWMAN.
